UNITED STATES PATENT OFFICE.

WALTER F. MOTTIER, OF GIBSON CITY, ILLINOIS.

HYDRAULIC MOTOR.

No. 870,379.

Specification of Letters Patent.

Patented Nov. 5, 1907.

Application filed March 12, 1907. Serial No. 362,022.

To all whom it may concern:

Be it known that I, WALTER F. MOTTIER, a citizen of the United States, residing at Gibson City, in the county of Ford and State of Illinois, have invented 5 new and useful Improvements in Hydraulic Motors, of which the following is a specification.

This invention relates to a reciprocating or other fluid motor, and it embodies novel means for automatically actuating valves for controlling admission 10 of water or other fluid to opposite sides of a piston or pistons for the purpose of obtaining the reciprocating action desired.

The object of the invention is to provide a motor of this class which may be used in connection with a pump 15 at any time or wherever a reciprocating motion is desired, and wherever a head of water or fluid under pressure is available, and which shall be simple in construction and thoroughly efficient in operation.

With these and other ends in view which will readily 20 appear as the nature of the invention is better understood, the same consists in the improved construction and novel arrangement and assemblage of parts which will be hereinafter fully described and particularly pointed out in the claims.

25 In the accompanying drawing has been illustrated a simple and preferred form of the invention; it being, however, understood that no limitation is necessarily made to the precise structural details therein exhibited, but that changes, alterations and modifications 30 within the scope of the invention may be resorted to when desired.

In the drawing, Figure 1 is a longitudinal sectional view of the motor with the parts in one position. Fig. 2 is a longitudinal sectional view showing the parts in 35 the opposite position.

Corresponding parts in both figures are denoted by like characters of reference.

It is desired to state at the outset that the relative 40 position of the main cylinder and the cylinders constituting the valve chest casings may be changed as desired, provided that the connections are maintained in substantially the form shown; for convenience of description the terms "right" and "left", and other relative terms will be used with reference to the form 45 illustrated in the drawings; and the construction of the motor will be described in connection with its operation to enable both to be more readily understood.

The water or other fluid enters under pressure 50 through a supply pipe 1 provided with branches 2 and 3 connected with the primary valve casing 22 and the secondary valve casing 21 about centrally between the heads or ends of said valve casings. The primary valve casing 22 contains a valve formed of a rod 23 carrying four spaced pistons 24^a, 24^b, 24^c and 24^d 55 which are moved simultaneously to open and close certain connections as will hereinafter appear.

The secondary valve casing 21 contains a valve formed of five spaced pistons 25^a, 25^b, 25^c, 25^d and 25^e mounted upon and connected by a rod 26 whereby they are moved simultaneously to open certain connections 60 as will hereinafter appear.

The water or motive fluid entering the valve casing 21 through the pipe 3 at the middle thereof, as shown in Fig. 1, passes between pistons 25^b and 25^e through ports 11 and 12 and a connecting duct or pipe A into 65 the left end of the valve casing 22, forcing the pistons to the right end thereof, as shown in said Fig. 1.

The motive fluid from the source of supply enters the middle of valve casing 22 through induction pipe 2 passing between the pistons 24^b and 24^e and through 70 ports 4 and 6 and a connecting duct B from the valve casing 22 to the right end of the main cylinder 20 which has therein two spaced pistons 27^a and 27^b connected by a piston rod 28 which operates through a gland 19 in the head of the cylinder. The fluid so 75 entering under pressure through the ports 4 and 6 and connecting duct B forces the pistons in the main cylinder 20 to the left end thereof, to the position shown in Fig. 2. Part of the water so admitted passes through a port or duct 8 which is located so as to be opened at the 80 end of the stroke into the right end of valve casing 21, forcing the pistons to the left end of said casing to the position shown in Fig. 2, and this forces the water from the left end of said casing through a port or duct 17 into the main cylinder 20 between the pistons 27^a 85 and 27^b, and out through an eduction pipe 18 connected with said main cylinder near the middle thereof. This movement of the pistons in the valve casing 21 separates the inlet pipe or port 3 from the port 11 and likewise separates the ports 9 and 15, and places in 90 communication the ports 11 and 16, and likewise the port 9 and the inlet pipe or port 3, as will be seen in Fig. 2. Water passes through the induction pipe 3 between the pistons 25^e and 25^d through ports 9 and 10 and a connecting duct C which connects the space 95 in the secondary valve chest adjacent to the induction pipe with the right end of the primary valve chest, forcing the pistons in the latter to the left end thereof, as shown in Fig. 2 and forcing the water or fluid from the left end of valve casing 22 out through 100 ports 12 and 11 and connecting duct A, through valve casing 21 between the pistons 25^b and 25^c, and through the port or duct 16 into the main cylinder 20 between the pistons 27^a and 27^b and out through the discharge pipe 18. When the pistons 27^a and 27^b in 105 the main cylinder 20 are moved to the left, the pistons in the valve casing 22 are in the position shown in Fig. 1, and the water or fluid from the left end of the main cylinder is free to pass through ports 7 and 5 and connecting duct D to the space between the pistons 110 24^a and 24^b in the valve casing 22 which is connected through an eduction pipe or port 13 which is connected

with the space in the main cylinder between the pistons in the latter which is constantly open to the exhaust.

When the pistons in valve casing 22 take the position shown in Fig. 2, fluid from the source of supply passes through the pipe or port 2 between the pistons 24^b and 24^c in said valve casing 22 and through the ports 5 and 7 and connecting duct D to the left end of the main cylinder 20 forcing the pistons to the position at the right end of the latter which is shown in Fig. 1. This action of the pistons in the valve casing 20 forces the water from the right end thereof through the ports 6 and 4 and connecting duct B into the space between the pistons 24^d and 24^a in valve casing 22 and through the port or pipe 14 which connects said space with the exhaust space between the pistons in the main cylinder.

A portion of the water or fluid entering the left end of the cylinder 20 passes through the port or duct 17 into the left end of the valve casing 21 forcing the pistons to the right end of the latter as indicated in Fig. 1. This movement of the valve forces the water from the right end of casing 21 through the port or duct 8 into the exhaust space between the pistons in the main cylinder and out through the eduction pipe 18. This latter motion of the valve in the casing 21 disposes the valve pistons in a position to separate the inlet port or pipe 3 from the port 9 and likewise to separate the ports 11 and 16 while the induction pipe or port 3 is placed in communication with the port 11, and the ports 9 and 15 are likewise placed in communication with each other, as shown in Fig. 1.

The water or fluid from the source of supply will then pass through the pipe or port 3 into the valve casing 21 between the pistons 25^b and 25^c, and through the ports 11 and 12 and connecting duct A into the left end of the valve casing 22, forcing the pistons in the latter to the right end thereof, and forcing the water from the right end of said valve casing through the ports 10—9 and connecting duct C into the valve casing 21 between the pistons 25^c and 25^d, thence through the port or duct 15 into the exhaust space between the pistons in the main cylinder, and out through the eduction pipe 18. This movement of the

pistons in the valve casing 22 separates the port 5 from the inlet 2 and the port 4 from the exhaust port 14 while the port 4 is placed in communication with the inlet 2 and the ports 5 and 13 are placed in communication with each other. Fluid may now pass from the source of supply through the ports or passages 2, 4, B 50 and 6 to the right end of the main cylinder 20, and the action is repeated.

The operation of the motor as hereinbefore described causes the respective valve pistons to pass to one side or the other of the respective ports, as will be readily understood. The action of the valves is positive and automatic, and the entire motor is characterized by simplicity and cheapness of construction.

Having thus fully described the invention, what I claim as new is:—

In a fluid motor of the character described, a cylinder, a piston rod mounted for reciprocation therein, and extending through one of the heads thereof, two suitably spaced pistons upon said rod, a primary valve chest, a valve rod mounted for reciprocation in the latter, four pistons suitably spaced upon said rod, ports and ducts so connecting the ends of the cylinder with the primary valve chest that in the various positions of the valve rod, one of said connections will be open and the other closed to the supply, a secondary valve chest, a valve rod mounted for reciprocation in the latter, five suitably spaced pistons upon said valve rod, four ports so connecting the secondary valve chest with the cylinder that in each terminal position of the piston rod in the latter, three of said ports shall communicate with the space between the pistons while the fourth port shall communicate through the ports and ducts aforesaid with the primary valve chest, ports and ducts constantly connecting the spaces between the terminal pistons upon the valve rod in the primary valve chest with the space between the pistons in the cylinder, an eduction port in the space intermediate the pistons in the cylinder, means for supplying fluid under pressure to the valve chests centrally between the ends thereof and ports and ducts connecting the spaces adjacent to the central piston in the secondary valve chest with the spaces between the terminal pistons in the primary valve chest and the heads of the latter.

In testimony whereof, I affix my signature in presence of two witnesses.

WALTER F. MOTTIER.
